UNITED STATES PATENT OFFICE.

CHARLES M. MARS, OF DORCHESTER, MASSACHUSETTS, ASSIGNEE, BY MESNE ASSIGNMENTS, TO BARBER-COLMAN COMPANY, OF ROCKFORD, ILLINOIS, A CORPORATION OF ILLINOIS.

TEXTILE-MACHINE.

1,381,653.

Specification of Letters Patent. Patented June 14, 1921.

Application filed July 10, 1916. Serial No. 108,407.

To all whom it may concern:

Be it known that I, CHARLES M. MARS, a citizen of the United States, and a resident of Dorchester, in the county of Suffolk 5 and State of Massachusetts, have invented an Improvement in Textile-Machines of which the following description, in connection with the accompanying drawings, is a specification, like characters on the drawings 10 representing like parts.

This invention relates to textile machines, being more particularly concerned with machines for selecting and separating warp threads and presenting them successively to 15 the action of some mechanism, such, for example, as a thread placing device or member. For purposes of illustration, the invention is herein shown embodied in a warp drawing or thread placing machine where 20 the thread placing device is utilized for placing the warp threads through drop wires, harness eyes and reed dents. While my invention has particularly advantageous 25 application for a machine of this class, it is, however, susceptible of broad application to machines intended for other or similar purposes than drawing-in machines wherein the selection and separation of warp or other threads is required. 30 The character of the invention will be best understood by reference to the following description of an illustrative embodiment thereof, shown in the accompanying drawings, wherein—

Figure 1 is an end elevation of a warp drawing machine constituting the preferred embodiment of my invention;

Fig. 2 is a front elevation of the left hand end of said machine;

Fig. 3 is a detail partially in end elevation and partially in vertical section, on an enlarged scale, of the means for driving the lower portion of the warp support for a plurality of warps;

Fig. 4 is a detail end elevation of a part of the means for driving the said lower portion of said warp support;

Fig. 5 is a front elevation of the construction shown in Fig. 4;

Fig. 6 is a plan view of the form of comb means preferably employed by me in separating the two sets of warps, the central portion thereof being broken away, the clamp whereon the comb is mounted being 55 also indicated;

Fig. 7 is a front elevation thereof;

Fig. 8 is a transverse section upon the line 8—8 of Fig. 6; and

Fig. 9 is a transverse section upon the line 9—9 of Fig. 6.

While the invention in many of its aspects is applicable to machines other than warp drawing machines and also to warp drawing machines of other types and constructions than that herein shown, I have 60 herein illustrated the invention by embodiment in a well known type of drawing-in machine which therefore need not be described in entire detail.

The machine here shown may, as to certain features thereof, be of the same general construction as the type of machine shown in British Patent No. 4661 of 1904 and the United States patent to Charles Lea, No. 1,153,869, dated September 14, 1915. 70

In the illustrated form of machine, as is well known to those skilled in the art, the heddles, warp threads and drop wires or other similar loom elements which may be and preferably are employed, are supported 80 in a general parallel arrangement lengthwise the machine upon suitable supports carried by the main frame 1 of the machine. Any suitable thread placing device is provided. I have herein represented a drawing needle 85 2 adapted to be suitably reciprocated and carried by a traveling carriage 3 indicated in Fig. 1 and preferably similar in construction and mode of operation to the corresponding carriage shown in the co-filed 90 application of Edgar F. Hathaway for textile machines, Serial No. 108,388. The said carriage with its needle is caused to traverse the extent of the reed which is or may be supported in the usual manner and is not 95 herein indicated, as well as the extent of the heddles, likewise omitted. The drawing needle is also traversed the extent of the drop wires if the latter be employed, such drop wires being of any suitable construction, not herein necessary to disclose and being similar if desired to those indicated in the co-pending application of Edward La Chance and Joseph Pennell, Serial No. 877,769, filed December 17, 1914.

The needle carriage 3 is positively traversed through the machine by means operatively related to the main operating or drive shaft 4, whereby, as more fully hereinafter set forth, the needle carriage and a portion 100 105 110

of the support for a plurality, and herein, a pair of warps, are positively and preferably differentially traversed through or longitudinally of the machine by means of operating connections from the said main drive shaft 4. The warp supporting means, or rather a portion thereof, as herein set forth, is traversed through the machine differentially with respect to the travel of the 10 needle carriage 3. The differential movements of said parts are movements at different rates. As hereinafter more fully set forth, I provide means preferably but not necessarily hand controlled for effecting a 15 compensating movement of the warps, such compensating movement being generally defined as a movement intended substantially continuously to counteract momentary variations. It is not, however, to be understood 20 that such compensating movements must occur continuously, as they may be caused to occur at any suitable time.

In the usual manner, the drawing needle 2 places successive warp threads through 25 the desired heddle eye, selected reed dent, and drop wires, these being appropriately positioned for the purpose in the needle path by suitable selecting and positioning mechanism. The drawing-in needle 2 may 30 be operated in any suitable manner. In order to operate the same and the other portions of the mechanism, I preferably provide means similar to those shown in the 35 said co-filed application of Edgar F. Hathaway. As clearly indicated in Fig. 1, the shaft 4 is provided upon its left hand end with a sprocket gear 5 about which passes a sprocket chain 6 also passing about a 40 sprocket gear 7 upon a shaft 8 having thereon a change gear mechanism diagrammatically indicated at 9 and conveying motion to a short shaft 10. The shaft 10 is provided with a sprocket gear 11 about which passes a sprocket chain 12 also passing about 45 a sprocket pinion 13 on a shaft 14, which as most clearly shown in Figs. 4 and 5, is provided with a cam 15, whereby through the connections hereinafter described a portion 50 of one of the warp supports, and herein, the lower clamp that receives both sets of warps, receives a traverse motion longitudinally of the machine, said motion being differential with respect to the needle carriage and also compensating with respect thereto, 55 if desired, as hereinafter set forth.

The needle carriage 3, hereinbefore referred to as positively traversed through the machine, is preferably provided for that purpose with a divided nut, not herein shown, but similar to that indicated in the 60 said co-pending application of Edgar F. Hathaway, and adapted to engage a suitable thread upon the cam shaft 14 which thus constitutes a lead screw shaft for traversing the needle carriage through the ma-

chine and a cam shaft for effecting the traverse of a portion of the warp supporting means longitudinally of the machine. While the means for thus positively and differentially operating the needle carriage and a 70 warp supporting means broadly, may be that disclosed in the co-pending application of Field, Lanning, Hathaway & Blanchard, Serial No. 142,251, filed February 6, 1903, the warp supporting means differs in many 75 respects from that shown in said application, as will hereinafter more fully appear. Obviously the warp support herein disclosed is capable of use in other relations, and particularly in other types of uniting or warp 80 drawing machines, and may for example be employed in connection with a single sheet or group of warps.

The drawing-in needle 2 may be operated in any suitable manner, and herein from the 85 main drive shaft 4 in the manner shown in said co-pending application of Edgar F. Hathaway. In this or in any other suitable manner, shaft 16 upon the needle carriage is rotated. The said shaft is provided with 90 a crank wheel 17 connected by rod 18 with a lever arm 19, the lower end whereof is fulcrumed upon the needle carriage 3 and the upper end whereof is connected by a link 20, to the holder for the needle 2 whereby the latter is reciprocated in a suitable 95 guide provided therefor.

The separate banks or groups of drop wires are supported or threaded upon a corresponding number of longitudinally extending bars 21 shown in Fig. 2. These bars 100 may be loom bars or special bars onto which the drop wires are transferred from the loom bars. I preferably provide suitable releasing means for said drop wires, generally 105 similar to those disclosed in the said application of Edgar F. Hathaway and in conjunction therewith I provide suitable drop wire feeding worms 22 corresponding in number to the number of banks of drop 110 wires. While the said drop wire feeding worms 22 may be operated in any suitable manner, I preferably impart a movement of continuous rotation to each of said worms 22 instead of an intermittent movement of 115 rotation as heretofore practised. The driving means for imparting such continuous movement of rotation may be and preferably is the same as that disclosed in the 120 said application of Hathaway.

In order to release the drop wires upon the bars 21, I preferably provide releasing keys corresponding in number to the number of sets of drop wires and each mounted upon a shaft, the rotation whereof is controlled by suitable pattern mechanism, as disclosed in the said application of Hathaway.

The pattern mechanism employed by me is so constructed and arranged that the releas-

ing key shafts may be operated in any combination or sequence or variable order that is desired, thereby to release drop wires from the bars 21 in any variable order to 5 the feeding action of the feed worms 22. For example, the said shafts and the warp worm shafts hereinafter described and which are also controlled by the pattern mechanism may be operated in a repeated sequence to 10 present warp threads and drop wires to the needle, or a plurality of threads may be presented by one worm shaft followed by the presentation of a plurality of threads by another worm shaft, or the said worm shafts, 15 or any two of them, may be operated simultaneously to present threads to the needle, so that two warps would be drawn in at the same time. The feeding of warp threads by each of the warp worms is therefore independent 20 of the feeding of warp threads by the other warp worm, and the same is true of the releasing of the drop wires as well as the feeding of the heddles, hereinafter referred to.

25 In the disclosed embodiment of the invention I provide means to support two warps, both of said warps being supported at one portion thereof by a single clamp or clamp members adapted to be automatically, differentially and compensatingly traversed longitudinally of the machine with respect to the 30 needle carriage. In the disclosed embodiment of the invention, both warps are supported at another portion thereof by a single clamp or clamp members not automatically traversed longitudinally of the machine but so supported that if desired manual adjustment may be effected longitudinally of the machine. In order to preserve distinct 35 threads pertaining to the two warps I preferably provide suitable means hereinafter described and herein carried by or supported upon the automatically traversed clamp or clamp members. I also provide for the hand control of the automatically traversed warp clamp or clamp members, thereby to effect compensating movement thereof, while, as 40 previously stated, I provide for the pattern control of the individual warp threads of the two sets of warps. These purposes and objects of my invention may be effected in 45 many different ways and I am not limited to effecting the compensating movement through hand control. I shall without in any 50 way limiting myself thereto proceed to describe the selected embodiment of means for effecting the desired result.

55 Referring more particularly to Figs. 1 and 3, I have in Fig. 1 represented two warp beams 23, 24, the threads 25, 26 thereof passing through a suitable two-part clamp 27, mounted for sliding movement longitudinally of the machine in two bifurcated guides 28 provided in suitable brackets 1, 60 one at each end of the machine and sup-

ported in the end uprights of the frame. The warp threads 26 also pass through a suitable comb hereinafter described whereby they are kept distinct from the warp threads 25 and by which manual relative or actual 70 compensating adjustment of the two sets of warps at this point may be effected.

The warp threads 25 extend from the clamp 27 to and about a warp worm 29 and thence to a second two-part clamp 30. The 75 said warp worm 29 is suitably and herein loosely supported at the left hand end of the machine in a bracket 31 as indicated in Fig. 1 and at the opposite end of the machine it is suitably supported for rotative movement 80 imparted thereto in any suitable manner. The said warp worm 29 and the corresponding warp worm for the other set of warp threads together constitute separating, selecting and feeding mechanism for the individual warp threads. Preferably each warp worm comprises a frusto-conical, fluted portion, which first receives, disentangles and separates the warp threads, and a selective feeding or spacing screw or worm portion by 85 which the threads are presented to the hook of the drawing-in needle 2 successively.

The warp threads 26 from the second warp beam after passing through the comb hereinafter more particularly described, pass about 90 the warp worm 32 supported in general parallel relation to the warp worm 29 in the said bracket 31 and driven in any suitable manner and from thence the said warp threads 26 pass through the said two-part 95 clamp 30, said two warp worms 29, 32 being within convenient range of the drawing-in needle 2.

The two warp worms 29, 32 are each intermittently driven from the main drive shaft 105 4 and the intermittent driving thereof is controlled by pattern mechanism preferably similar to that disclosed in the said co-pending application of Edgar F. Hathaway, whereby said warp worms 29, 32 are independently rotated. Thus, in the disclosed embodiment of my invention, I selectively drive through the pattern mechanism the warp worms 29, 32 and the release key shafts 110 for the drop wires, and in addition I also so drive through the control of the pattern mechanism the heddle selecting elements as hereinafter set forth.

115 In the disclosed embodiment of the invention wherein I have provided a clamp 27 previously described for supporting both sets of said warp threads but in a separated manner by reason of the employment of said comb or other suitable mechanism, any suitable means may be provided whereby the 120 clamp 27 may be traversed longitudinally of the machine and differentially and also compensatingly with respect to the needle carriage. Preferably, however, I have as previously stated provided the cam 15 upon the 125 130

lead screw cam shaft 14. In order to convey motion from the said cam 15 to the said clamp 27, I have herein provided the following co-acting instrumentalities, to which, however, my invention is in no wise limited.

Upon a stud 33, shown in Figs. 1, 4 and 5, is pivoted a lever 34, provided with a projection 35 adapted to be held against the cam 15 by a spring 36. If desired, said lever 34 may be held in non-active position by a latch 36'. To the upper slotted end of said lever 34 is adjustably secured a link 37, the outer end of which is pivotally connected at 38 to a lever 39. The lever 39 is rigidly attached 15 to a pivot or pin 40 which is pivotally mounted in a lever 41. The lever 41 is pivotally supported on a stud 42 extending from the framing and having loosely mounted thereon a worm 43 carrying or having integral therewith a wheel 44 with which engages a pawl 45 fixed upon said pin 40. On the lever 41 is a stop screw 41^a against which the lever 39 is pulled by the spring 36. When the cam pushes the link 37 endwise, the lever 25 39 swings away from the stop screw and the pawl 45 swings into contact with the wheel 44, whereby in the rotation of said screw shaft 14, the cam 15 imparts intermittent rotation to the said worm 43.

30 In order to transmit motion to the said clamp 27 from the said worm 43, I have provided said clamp with a rack 46 (Fig. 6) formed upon or attached to the inner face thereof and with the teeth of which the said 35 worm 43 meshes, whereby said clamp is traversed along the machine in an automatic manner.

In addition to the automatic control of the clamp 27 whereby differential traverse of the 40 two sets of warp threads may be secured with respect to the needle carriage, I preferably provide for a compensating movement and herein secure the same by a hand control of the said clamp 27. While for this purpose 45 I may provide any suitable means I have herein represented two lever arms 47, one of which is indicated in Fig. 1 as pivotally mounted at 48 upon one end upright of the frame, the other lever arm being similarly 50 mounted at the other end of the machine. Each of said lever arms 47 has pivotally connected thereto intermediate its ends a link 47' pivotally connected at its upper end at 49 to a lever arm 50, itself pivoted at 51 upon the machine frame, thereby providing 55 parallel motion means to effect and secure the proper movement of said lever arms 47.

The outer free ends of said lever arms 47 are provided with suitable bearings wherein 60 is loosely mounted for manually imparted axial movement a manually rotated shaft 52 having splined thereon a pinion 53 adapted to mesh with the pinion 54 fast with a sprocket gear 55 loosely mounted upon a 65 stud or pin 56 itself supported in a block

57 adjustably secured by set screw 58 upon an arm or fixed shaft 59 outwardly extending from the adjacent end upright of the machine frame. Passing about and meshing with the said sprocket gear 55 is a sprocket 70 chain 60 which passes about a sprocket gear 61 fast with the worm 43 heretofore described. The pinion 53 is, as stated, splined upon the shaft 52 herein formed as a tube, whereby said pinion may remain in mesh 75 with the pinion 54 while permitting longitudinal movement of said shaft 52 preferably manually, whereby to control the clutch mechanism of the machine in a manner similar to that disclosed in the patent to Hathaway & Lea, No. 1,169,087, dated January 18, 1916. In this manner the machine may be stopped or started by the operator wherever he may be positioned between the ends thereof. The said shaft 52 receives a swiv- 80 eled plug that is preferably bifurcated at its ends for the passage of the upper curved portion of an upright lever operatively connected in a manner not herein necessary more fully to describe with the clutch of the 85 machine. When it is not desired to impart hand adjustment to the warp clamp 27, the shaft 52 may if desired be swung into an elevated or non-active position by a movement of the lever arms 47 upwardly, the lat- 90 ter being then supported in such non-active position by any suitable latch or other means not herein necessary more fully to describe.

The clamp 30 which receives both sets of warp threads 25, 26 is supported at each end 100 of the machine in a generally U-shaped bracket 62 adjustably supported by means of a set screw 63 upon a lever arm 64 pivotally and adjustably supported at 65 upon the framing 1^a of the machine whereby through 105 the change of position of said lever arms 64, the clamp 30 may be so positioned as to properly tension and position the warp threads. The warp clamp 30 may be moved longitudinally of the lever arms 64 and if 110 desired compensating hand adjustment of the clamp 30 may be effected by manually moving said clamp in and longitudinally of the two brackets 62. This may be done, if desired, to alter the position of the thread 115 end for any purpose.

The pattern mechanism herein referred to for controlling certain specified parts may be and preferably is that disclosed in the co-filed application of Hathaway & Mars, Serial No. 120 108,887, filed July 10, 1916. The comb is indicated generally at 102 (Fig. 9) having teeth 104 received in bottom and top bars 103, 106, the latter being readily removable. Said comb is held in a clip 91, 92, which is 125 formed in two parts normally grasping the comb through the action of the coil spring 94 surrounding the pin 95. As shown in Fig. 7 two such sets of spring clips are employed.

The said comb is supported upon one 130

member of the clamp 27 by means of a sprocket chain 88 mounted upon sprocket pinions 85, 87, respectively received upon studs 82, 83, in the said clamp 27. The stud 5 82 is provided with a hand-wheel 89 for rotation thereof, whereby the comb may be moved longitudinally of the clamp. Springs 100 are employed to assist in supporting the comb and its clips upon the sprocket 10 chain 88.

Referring more particularly to Fig. 1, the so-called bottom beam is shown at the left as 23, and the top beam or spool is shown at the right as 24. In referring hereafter to 15 right or left, it is assumed that the operator is facing the machine at the warp side of the latter. According to one method, the warps may be placed in the machine substantially as follows.

20 One part of the warp end clamp 30 should be placed on the bottom beam, as though it were to be clamped for single beam work. The sheet of threads from the top beam should be held under tension in a suitable 25 clamp (not shown). This top sheet under tension should be placed on the bottom sheet already on the lower section of the warp end clamp 30 and preferably the top sheet is placed about one half inch to the right instead of having the left-hand edges of both 30 sheets in the same vertical plane. The upper part of the warp end clamp 30 is placed in position, the superfluous yarn ends are cut off, and the warp end clamp clips are applied. 35 The comb 103 and its cover are properly placed in the top sheet and held therein by the adjustable clips provided therefor. The warps are now ready to be placed in the machine and the truck (not shown) is moved 40 forward, so that the center line of the bottom beam is about under the clamp 27.

In loading the machine, it is desirable that the operator have an assistant, the operator standing at the left and the assistant at the 45 right. Facing each other, they may lift the warp end clamp 30 and place it in the special hangers (not shown) suspended from the top harness jack studs, the operator holding back the bottom beam, while the assistant holds back the top beam to keep the proper tension. The operator should next 50 place the rod 107 (Fig. 1) between the sheets. The operator and helper then slide the comb 103 forward. While still holding the comb 55 with one hand, they remove the outer section 75 of the clamp 27 from its place in the holes at the top of the machine and lock it in its proper position, allowing the comb 103 to rest upon the clamp 27 and against 60 the angle pieces 76 (Fig. 6) which are fastened at its inner portion. The wire hooks 100 which are fastened to the clips 91-92 are next attached to convenient links of the chain 88 carried upon the outer section of 65 the warp clamp, so that the top sheet of

warps held within the comb may be moved endwise manually independent of the bottom sheet. The warp worm shafts may then be placed in the machine, the clamp 30 put in the brackets 62, and the rod 107 placed 70 in the holders 108.

Having thus described one illustrative embodiment of my invention, I desire it to be understood that although specific terms are employed, they are used in a generic 75 and descriptive sense and not for purposes of limitation, the scope of the invention being set forth in the following claims.

Claims—

1. Textile mechanism comprising in combination, drawing-in mechanism, means for supporting a plurality of groups of warp threads, and automatic traversing means combined with compensating means for a portion only of the support for said groups 80 of warp threads.

2. Textile mechanism comprising in combination, drawing-in mechanism, means for supporting with preserved distinctness a plurality of groups of warp threads, and automatic traversing means combined with compensating means for a portion only of the 90 supporting means for said groups of warp threads.

3. Textile mechanism comprising in combination, drawing-in mechanism, two distinct means co-operating together to support a plurality of groups of warp threads, and automatic traversing means combined with compensating means for one only of 95 100 said distinct supporting means.

4. Textile mechanism comprising in combination, drawing-in mechanism, means for supporting a plurality of groups of warp threads, said means comprising two clamps, 105 and automatic traversing means combined with compensating means for one only of said clamps.

5. Textile mechanism comprising in combination, drawing-in mechanism, means for supporting with preserved distinctness a plurality of groups of warp threads, said means including upper and lower clamps, and automatic traversing means combined with compensating means for said lower 115 clamp only.

6. Textile mechanism comprising in combination, drawing-in mechanism, means for supporting a plurality of groups of warp threads, said means including two clamps, 120 means for preserving distinct the warp threads entering one of said clamps, and automatic traversing means combined with compensating means for at least one of said clamps.

7. Textile mechanism comprising in combination, thread selecting mechanism, means common to such groups for supporting a plurality of groups of warp threads, and automatic traversing means combined with com- 130

pensating means for a portion only of the support for said groups of warp threads.

8. Textile mechanism comprising in combination, thread selecting mechanism, means common to such groups for supporting with preserved distinctness a plurality of groups of warp threads, and automatic traversing means combined with compensating means for a portion only of the supporting means for said groups of warp threads.

9. Textile mechanism comprising in combination, thread selecting mechanism, two distinct means common to such groups and coöperating together to support a plurality of groups of warp threads, and automatic traversing means combined with compensating means for one only of said distinct supporting means.

10. Textile mechanism comprising in combination, thread selecting mechanism, means common to such groups for supporting a plurality of groups of warp threads, said means comprising two clamps, and automatic traversing means combined with compensating means for one only of said clamps.

11. Textile mechanism comprising in combination, thread selecting mechanism, means common to such groups for supporting with preserved distinctness a plurality of groups of warp threads, said means including upper and lower clamps, and automatic traversing means combined with compensating means for said lower clamp only.

12. Textile mechanism comprising in combination, thread selecting mechanism, means for supporting a plurality of groups of warp threads, said means including two clamps, means for preserving distinct in a plurality of groups the warp threads entering one of said clamps, and automatic traversing means combined with compensating means for at least one of said clamps.

13. Drawing-in mechanism comprising in combination, a drawing-in needle, a carriage therefor, means to traverse said carriage, means common to such groups to support a plurality of groups of warp threads, and automatic traversing means combined with compensating means for a portion only of said warp supporting means.

14. Textile mechanism comprising in combination, a drawing-in needle, a carriage therefor, means to traverse said carriage, means to support a plurality of groups of warp threads, said means including two clamps, and means to impart compensating traversing movement to one only of said clamps.

15. Textile mechanism comprising in combination, a drawing-in needle, a carriage therefor, means to traverse said carriage, means for supporting a plurality of groups of warp threads, said means including two clamps, means to preserve distinct the groups of threads passing through one of

said clamps, and compensating traversing means for at least one of said clamps.

16. Textile mechanism comprising in combination, a drawing-in needle, a carriage therefor, means to traverse said carriage, means for supporting with preserved distinctness a plurality of groups of warp threads, said means including two clamps, and automatic traversing means combined with compensating means for one only of said clamps.

17. Textile mechanism comprising in combination, a drawing-in needle, a carriage therefor, means to traverse said carriage, means for supporting a plurality of groups of warp threads, said means including two clamps, means at one of said clamps for preserving distinct the groups of warp threads passing through one of said clamps, and automatic traversing means combined with compensating means for one of said clamps.

18. Textile mechanism comprising in combination, a drawing-in needle, a carriage therefor, means to traverse said carriage, means for supporting a plurality of groups of warp threads, said means including two clamps, means at one of said clamps for preserving distinct the groups of warp threads passing through the last mentioned clamp, and automatic traversing means combined with compensating means for one of said clamps, said other clamp being manually adjustable.

19. Textile mechanism comprising in combination, thread selecting mechanism, means for supporting a plurality of groups of warp threads, said means including two clamps, and a comb carried by one of said clamps for coöperation with one of said groups of warp threads.

20. Textile mechanism comprising, in combination, drawing-in mechanism, means for supporting a plurality of groups of warp threads, said means including two clamps, a comb carried by one of said clamps and having one group of warp threads, and means for imparting automatic traversing movement to said groups of warp threads combined with compensating means for one of said groups.

21. Textile mechanism comprising in combination, drawing-in mechanism, means for supporting a plurality of groups of warp threads, said means including two clamps, a comb carried by one of said clamps, and co-operating with one only of said groups of warp threads, and automatic traversing means combined with compensating means for one of said clamps.

22. Textile mechanism comprising in combination, drawing-in mechanism, means for supporting a plurality of groups of warp threads, said means including two clamps, a comb carried by one of said clamps and co-operating with one only of said groups of

warp threads, and automatic traversing means combined with compensating means for the clamp that carries said comb.

23. Textile mechanism comprising in combination, drawing-in mechanism, means for supporting a plurality of groups of warp threads, said means including two clamps, a comb carried by one of said clamps, and automatic traversing means combined with compensating means for the last mentioned clamp, the other clamp being manually adjustable.

24. Textile mechanism comprising in combination, drawing-in mechanism, means for supporting a plurality of groups of warp threads, said means including two clamps, a comb carried by one of said clamps, and means for adjusting said comb.

25. Textile mechanism comprising in combination, drawing-in mechanism, means for supporting a plurality of groups of warp threads, said means including two clamps, a comb carried by one of said clamps, and manual means for imparting compensating traversing movement to said comb.

26. Textile mechanism comprising in combination, drawing-in mechanism, means for supporting a plurality of groups of warp threads, said means including two clamps, a comb carried by one of said clamps, means for imparting compensating movement to said comb, and automatic traversing means combined with compensating means for the clamp that carries said comb.

27. Textile mechanism comprising in combination, drawing-in mechanism, means for supporting a plurality of groups of warp threads, said means including two clamps, a comb carried by one of said clamps, means for imparting compensating movement to said comb, and automatic traversing means combined with compensating means for the clamp that carries said comb, the other clamp being manually adjustable.

28. Textile mechanism comprising in combination, drawing-in mechanism, means for supporting a plurality of groups of warp threads, and automatic traversing means for a portion only of the support for said groups of warp threads, manual means for imparting compensating traversing movement to said groups of warp threads.

29. Textile mechanism comprising in combination, drawing-in mechanism, means for supporting with preserved distinctness a plurality of groups of warp threads, and automatic traversing means for a portion only of the supporting means for said groups of warp threads, manual means for imparting compensating traversing movement to said groups of warp threads.

30. Textile mechanism comprising in combination, drawing-in mechanism, two distinct means coöoperating together to support

a plurality of groups of warp threads, and automatic traversing means for one only of said distinct supporting means, manual means for imparting compensating traversing movement to said groups of warp threads.

31. Textile mechanism comprising in combination, drawing-in mechanism, means for supporting a plurality of groups of warp threads, said means comprising two clamps, and automatic traversing means for one only of said clamps, manual means for imparting compensating traversing movement to said groups of warp threads.

32. Textile mechanism comprising in combination, a plurality of thread selecting members, means common to such groups for supporting a corresponding plurality of groups of warp threads, selective means controlling said thread selecting members, and automatic traversing means combined with compensating means for a portion only of said groups of warp threads.

33. Textile mechanism comprising in combination, a plurality of thread selecting members, means common to such groups for supporting a corresponding plurality of groups of warp threads, selective means controlling said thread selecting members, and automatic traversing means combined with compensating means for a portion only of said groups of warp threads, the remaining portion of said supporting means being manually adjustable.

34. Textile mechanism comprising in combination, a plurality of warp worms, means for supporting a pair of groups of warp threads, said means including two clamps, and automatic traversing means combined with compensating means for one only of said clamps.

35. Textile mechanism comprising in combination, a plurality of warp worms, means for supporting two groups of warp threads, said means including two clamps, and means carried by one of said clamps for preserving distinct the groups of warp threads passing through the last mentioned clamp.

36. Textile mechanism comprising in combination, a plurality of warp worms, means for supporting two groups of warp threads, said means including two clamps, means for preserving distinct the groups of warp threads passing through one of said clamps and automatic traversing means combined with compensating means for one only of said clamps.

37. Textile mechanism comprising in combination, drawing-in mechanism, means for supporting a plurality of groups of warp threads, said means including two clamps, means between said clamps for separating said groups of warp threads, and means for traversing one only of said clamps.

38. Textile mechanism comprising, in combination, a drawing-in needle, two warp worms 29, 32, means for supporting a plurality of groups of warp threads including 5 a clamp 27, a comb operatively related thereto for receiving a portion of the threads in said clamp, and a clamp 30 for all said warp threads.
39. Textile mechanism comprising, in combination, a drawing-in needle, two warp worms 29, 32, means for supporting a plurality of groups of warp threads including 10 a clamp 27, a comb operatively related thereto for receiving a portion of the threads in 15 said clamp, a clamp 30 for all said warp threads, and automatic traversing means for a portion only of the support for said groups of warp threads.
40. Textile mechanism comprising, in combination, a drawing-in needle, two warp worms 29, 32, means for supporting a plurality of groups of warp threads including 20 a clamp 27, means for automatically traversing said clamp, and a manually adjustable 25 clamp 30.
41. Textile mechanism comprising, in combination, a drawing-in needle, two warp worms 29, 32, means for supporting a plurality of groups of warp threads including 30 a clamp 27, a comb supported thereon for a portion of the warp threads, and a manually adjustable clamp 30.
42. Textile mechanism comprising, in combination, a drawing-in needle, two warp worms 29, 32, and means for supporting a plurality of groups of warp threads including 35 a clamp 27 having means to separate the said plurality of groups of warp threads, and a clamp 30.
43. Textile mechanism comprising, in combination, a drawing-in needle, two warp worms 29, 32, means for supporting a plurality of groups of warp threads, including 40 a clamp 27 having a comb mounted thereon, 45 means automatically to traverse said clamp, and a clamp 30 adapted to receive all the warp threads of said plurality of groups.
44. Textile mechanism comprising in combination, a drawing-in needle, a traversing 50 carriage therefor, two warp worms 29, 32, means for supporting a plurality of groups of warp threads including a clamp 27, a comb operatively related thereto for receiving a group of the threads in said clamp, a 55 clamp 30 for all said warp threads, and automatic traversing means for a portion only of the support for said group of warp threads, the movement of said traversing means being differential with respect to the 60 movement of the drawing-in needle carriage.
45. Textile mechanism comprising in combination, drawing-in mechanism, means for supporting a plurality of groups of warp threads, said means including two clamps, a 65 comb carried by one of said clamps, and
- manual means for imparting traversing movement to said comb.
46. Textile mechanism comprising in combination, drawing-in mechanism, means for supporting a plurality of groups of warp 70 threads, and automatic traversing means for a portion only of the support for said groups of warp threads.
47. A support for textile material comprising independently supported supporting 75 members, a holder wherein one of said members loosely rests for manual positioning, and means for independently adjusting another of said members.
48. A support for textile material comprising independently supported supporting members, a fixed holder wherein one of said members loosely rests for manual positioning, and means for independently adjusting the other of said members. 80
49. A warp support for textile machines comprising two independent clamps, a fixed support wherein one of said clamps loosely rests for manual positioning, and means for independently adjusting the second clamp. 85
50. A warp support for textile machines comprising a holder U shaped in cross section, a clamp mounted to slide in said holder, a second clamp, and means for independently adjusting said second clamp. 90
51. A warp support for textile machines comprising two independent and independently mounted clamps, a holder wherein one of said clamps is loosely mounted for manual positioning, and a rack and gear for 100 adjusting the second clamp.
52. A warp support for textile machines comprising two independent and independently mounted clamps, fixed holding means for one of said clamps, and a rack and worm 105 directly engaging the second clamp.
53. A warp support for textile machines comprising two independent and independently mounted clamps, fixed holding means for one of said clamps, a rack and worm 110 directly engaging the second clamp, and an adjusting rod for said rack and worm extending longitudinally of the machine.
54. A warp support for textile machines comprising two clamps, fixed holding means 115 for one of said clamps, and means for independently adjusting the other clamp including a rod extending lengthwise the machine wherein the warp support is mounted.
55. A warp support for textile machines comprising in combination, two independent clamps, a fixed support whereon one of said clamps is mounted, means mechanically to adjust the second clamp, and a warp worm 120 shaft about which the warp threads are partially wrapped at an angle due to the location of the two clamps, whereby the adjustment of one clamp varies the angular relation of the warp threads to the warp worm. 125
56. A warp support for textile machines 130

comprising two clamps, automatic and hand means for adjusting one of said clamps, the second clamp being loosely mounted for hand positioning.

5 57. A warp drawing-in machine comprising a needle carriage, a needle mounted thereon, means for traversing said carriage, two independent clamps constituting a warp support, means automatically to traverse one 10 of said clamps, and a support for the second clamp wherein it is loosely mounted for hand positioning.

58. A textile machine having, in combination, stationary means for supporting a 15 clamp for holding two sheets of warp threads, another clamp for holding both of said sheets of warp threads, means for ad-

justing the position of the last mentioned clamp, and means for adjusting the position of one of said sheets of threads relatively to 20 the other sheet.

59. A textile machine having, in combination, stationary means for supporting a clamp for holding two sheets of warp threads, another clamp for holding both of 25 said sheets of warp threads, means for adjusting the position of the last mentioned clamp, and means adjacent to the last mentioned clamp for adjusting the position of one of said sheets of threads relatively to 30 the other sheet.

In testimony whereof I have signed my name to this specification.

CHARLES M. MARS.
